UNITED STATES PATENT OFFICE.

ALBRECHT SCHMIDT AND ADOLF STEINDORFF, OF HÖCHST-ON-THE-MAIN, GERMANY,
ASSIGNORS TO FARBWERKE VORM. MEISTER LUCIUS & BRÜNING, OF HÖCHST-ON-
THE-MAIN, GERMANY, A CORPORATION OF GERMANY.

MODE OF PREPARING FINELY-DIVIDED OR COLLOID INDIGO DYESTUFFS.

1,094,683.

Specification of Letters Patent. Patented Apr. 28, 1914.

No Drawing.

Application filed May 17, 1911. Serial No. 627,758.

To all whom it may concern:

Be it known that we, ALBRECHT SCHMIDT, Ph. D., chemist, and ADOLF STEINDORFF, Ph. D., chemist, citizens of the Empire of Germany, residing at Höchst-on-the-Main, Germany, have invented certain new and useful Improvements in the Mode of Preparing Finely-Divided or Colloid Indigo Dyestuffs, of which the following is a specification.

We have found that by producing indigo from indol derivatives which are closely related to indigo and capable of directly yielding indigo, in the presence of aromatic primary, secondary and tertiary bases and their derivatives, such as arylglycins or the like, and aromatic ammonium compounds, the indigo precipitates in an extremely finely-subdivided colloid-like form. By the term "indol derivatives which are closely related to indigo and capable of directly yielding indigo," we mean primarily indigo salts, comprising the salts of the dyestuff itself and those of its leuco compounds, that is to say, the leuco-indigo salts. Said aromatic bases act merely on the physical state of the indigo, like the aromatic sulfonic or carboxylic acids mentioned in United States Letters Patent 1,058,019 and 1,058,020, granted April 1, 1913, to Albrecht Schmidt, assignor.

Example: 100 parts by weight of anilin sulfate are dissolved in 3000 parts of sulfuric acid of 60° Bé., while stirring, and into this solution are strewed at a temperature of 15° C. 262 parts of indigo, whereby indigo sulfate is immediately formed. The indigo sulfate thus produced is then stirred for a short time (about one-half hour) with the excess of sulfuric acid and with the

anilin sulfate, until a homogeneous mass is formed. The thick mixture of the reaction is poured into a large quantity of ice-water which may advantageously contain in solution slight quantities of carbohydrates or similar substances.

In the place of anilin there may be used corresponding quantities of, for instance, toluidins, dimethylanilin, benzylanilin, dibenzylanilin, phenylglycin, phenyldiglycin, phenylhydrazin, naphthylanin, α - and β -aminoanthraquinone or other primary, secondary or tertiary bases; also quaternary ammonium compounds, such as dimethyl-phenylbenzylammonium-chlorid answer very well.

Having now particularly described our invention what we claim is:

1. The process of preparing a new form of synthetic indigo, which consists in subjecting derivatives of indol which are closely related to indigo and capable of directly yielding indigo, to indigo-producing conditions in the presence of aromatic bases.

2. The process of preparing a new form of synthetic indigo, which consists in producing the indigo from indigo salts in the presence of aromatic bases.

3. The process of preparing a new form of synthetic indigo, which consists in producing the indigo from leuco-indigo salts in the presence of aromatic bases.

In testimony whereof, we affix our signatures in presence of two witnesses.

ALBRECHT SCHMIDT.
ADOLF STEINDORFF.

Witnesses:

JEAN GRUND,
CARL GRUND.

It is hereby certified that in Letters Patent No. 1,094,683, granted April 28, 1914, upon the application of Albrecht Schmidt and Adolf Steindorff, of Höchst-on-the Main, Germany, for an improvement in "Mode of Preparing Finely-Divided or Colloid Indigo Dyestuffs," an error appears in the printed specification requiring correction as follows: Line 51, for the word "naphthylanin" read *naphthylamin*; and that the said Letters Patent should be read with this correction therein that the same may conform to the record of the case in the Patent Office.

Signed and sealed this 6th day of July, A. D., 1915.

[SEAL.]

R. F. WHITEHEAD,

Acting Commissioner of Patents.
